Primary Examiner — Robin V Webster*Assistant Examiner* — Keith J Wilson(74) *Attorney, Agent, or Firm* — James A. Joyce; Godfrey & Kahn, S.C.(57) **CLAIM**

The ornamental design for a rideable toy, as shown and described.

DESCRIPTION

FIG. 1 is a top front perspective view of a rideable toy showing our new design;

FIG. 2 is a bottom rear perspective view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a rear view thereof.

The broken lines in the figures show portions of the rideable toy that form no part of the claimed design.
